SPARK INTENSIFIER FOR SPARK PLUGS

Joseph Arthur Henry Castengay,
North Andover, Mass.

Application September 21, 1950, Serial No. 186,036

2 Claims. (Cl. 313—146)

1

This invention relates to spark intensifiers for automobiles and other internal combustion engines in suitable relation to high-tension high-voltage ignition systems thereof.

In order that the principle of the invention may be readily understood, I have disclosed several embodiments thereof in the accompanying drawings wherein—

Fig. 1 is a view, partly in elevation and partly in vertical section, of a distributor head of an automobile having spark intensifiers shown in operative position therein with relation to the spark plugs;

Fig. 2 is a view mainly in vertical central section, of a spark intensifier, having a through, air-circulation, spark-adjusting window, such spark intensifier being constructed to be snapped into the distributor head or cap, and showing the related wire cable;

Fig. 3 is a bottom view of the construction shown in Fig. 2;

Fig. 4 is a view generally similar to Fig. 2, but wherein the spark intensifier device is adapted to be screwed directly onto the spark plug;

Fig. 5 is a view generally similar to Fig. 4, but having the air-circulation window extending only halfway transversely through the body member;

Fig. 6 is a cross section of Fig. 5 on the broken line 6—6 thereof;

Fig. 7 is a view similar to Fig. 6, but without an air-circulation and spark-adjusting window;

Fig. 8 is a cross section upon the line 8—8 of Fig. 7;

Fig. 9 is a view in vertical section of a still further form of the invention;

Fig. 10 is a bottom view of the construction shown in Fig. 9;

Fig. 11 is a side elevation of the form of the invention shown in Fig. 9;

Fig. 12 is a view, partly in vertical section and partly in side elevation, of still another form of the invention;

Fig. 13 is a view, partly in vertical section and partly in side elevation, showing the spark intensifier inserted in the wire cable itself;

Fig. 14 is a side elevation of a spark intensifier having a through, air-circulation, spark-adjusting window as in Figs. 2, 4, 9 and 12, but differently supported in functioning position;

Fig. 15 is a vertical central section similar to Fig. 2, but showing the threaded extension of the member formed as screws adjustable by a screw-driver; and

Fig. 16 is a side elevation of the preferred form of spark intensifier.

2

The novel intensifier herein disclosed, termed the "spark master," intensifies or fattens the spark at the spark plug point and causes it to fire properly in any oil condition, even if the oil is hot and though the gap be extra wide or worn out, thereby providing the motor with extra pick-up and power, besides minimizing smoke screens in old motors and effecting more mileage. What I term the bulb or body member of the spark intensifier is made of some suitable plastic material that is translucent, preferably clear Lucite. The so-called bulb or body member, at substantially midheight or, otherwise stated, at mid-length may be provided with a "window" or perforation to prevent corrosion by allowing air circulation, and perfectly providing an easy manner of adjusting the points, as hereinafter fully stated, thereby adjusting or controlling the spark. As stated, the device intensifies the spark, prevents corrosion, and also provides a more powerful and visible spark which lets the car driver know at all times, upon inspection, the working condition of the spark plugs and of the ignition system.

The spark plug intensifier herein disclosed in several forms can be quickly taken apart and properly adjusted at any time. These spark intensifiers in their several forms are so constructed as to perform equally well wherever mounted, as for example whether mounted upon the individual spark plugs themselves, or upon the spark-plug wire cables, or upon the distributor head or cap. They are also extremely light in structure, and in each construction the bulb or body member is attached in a detachable manner at opposite ends or faces to separate parts of the ignition system. The broad purpose of this invention is to make the spark visible to anyone who turns on the power and thus provides current to the spark plugs.

Referring more particularly to the drawing, and first to Fig. 1, a distributor head or cap of an automobile is illustrated at 1. This may be of the usual form, but I preferably construct it of the translucent plastic known as clear "Lucite." Preferably integrally formed therewith are the upwardly projecting sockets 2, three of which are shown, which in practice are frequently seven in number. Each of the sockets 2 is provided with an inner socket member 3 constituting a part of the spark plug unit and which at its lower end within the distributor head 1 is provided with a spark plug contact 4 engaging a spark-plug contact 5 upon a springy strip 55 6 supported at 7.

The three spark intensifiers shown in Fig. 1 are each as a whole indicated at 2, and the construction thereof is the same as is shown in Figs. 2 and 3, to which I will now refer.

What I term the bulb or body member of the spark intensifier is represented at 9. It is desirably formed of some suitable translucent plastic insulating material, preferably clear "Lucite," which is shown as provided with a window or opening 10 extending, in this embodiment of the invention, all the way through the bulb or body member 9 and providing air circulation, thereby preventing corrosion. The opening 10 may be of any suitable diameter and form, and may be beveled or flaring at its ends, as indicated at 11. The opening is large enough for the insertion of a gauge, as will be explained. The opening 10 is preferably circular in cross section. Each bulb or body member 9 is preferably of a circular form in cross section, but not necessarily so. At the top and at the bottom, it is provided with a threaded opening 12, 13, respectively, and therein are received the threaded extensions 14, 15 of lengthwise-adjustable, tubular or cup-like members 16, 17, the former of which receives the wire cable end 18 and the latter of which is vertically slotted to provide two springy members or parts which snap into the spark plug socket member 3.

The distance apart of the extreme ends of the extensions 14, 15, and hence the extent of the spark gap, is very accurately established by providing a short, narrow strip or gauge of metal of just the right thickness, and inserting horizontally one end of it well into the window 10 and then screwing inward by the thumb and fingers one or both of the members 16, 17 until their inner ends 14, 15 both touch the upper and lower faces respectively of the properly inserted metal piece or gauge.

In Fig. 4 the spark plug as a whole is indicated at 18, it having a threaded lower end 18'. The upper end of it is provided with a threaded extension 19. The bulb or body member is indicated at 20. It is preferably of molded plastic, translucent material, such as clear Lucite, and it is shown as having a through-hole 21 like that shown in Fig. 2, preferably circular in diameter, but of any desired shape and for the same purpose. In the upper and lower faces of the bulb or body member 20 are threaded holes such as shown in Fig. 2, the lower end receiving the threaded extension 19 and the upper one receiving the threaded end 22 of the metal end 23 receiving the wire cable and threaded about the lower end of which is a nut 24.

The construction shown in Figs. 5 and 6 is for attachment to the screw type of spark plug as in Fig. 4, and it differs from that shown in Fig. 4 only in that the bulb or body member 25 has a window 26 which extends only halfway through the same, that is, to the threaded ends 19 and 22, and being of any suitable diameter.

The construction shown in Figs. 7 and 8 is the same as shown in Figs. 4, 5 and 6, excepting that the bulb or body member 27 has no opening or window, because it is molded with the adjustment taken care of in molding.

The construction shown in Figs. 9, 10 and 11 is one in which the bulb or body member 28 is of plastic, translucent material, preferably Lucite, that is molded about the set-screw end part 29 and the internally threaded part 30. There is provided a through-opening 31, here shown as of rectangular form in cross section. The part

29 may have a nut 32 which is molded into the bulb or body member 28. It may be hexagonal or of other form. In this form there is preferably the usual adjustment provided for the parts 29 and 30 in the bulb or body member 28.

In the construction shown in Fig. 12 the bulb or body member 32, also of translucent plastic material, preferably Lucite, is provided with a through-window 33, and preferably molded into said bulb or body member 32 is a tube 34 having a spur 35 at the lower end to make most effective contact with the wires of the cable end that is to be received in the open-ended tube 34. There is molded into the opposite end of the bulb or body member 32 a slotted end 36 to be snapped onto the spark plug.

The construction shown in Fig. 13 differs from what is shown in the preceding figures, in that the bulb or body member 37 is positioned directly in the wire cable itself, the two parts of which are shown at 38, 39. In this construction the bulb or body member 37 is provided with a through-opening or window 40 of any suitable diameter. The two parts of the cable 38, 39 are respectively provided with threaded metallic ends 41, 42 threaded into threaded holes in the bulb or body member, as in Figs. 2 and 4, for example, so that the spark gap may be accurately adjusted or established, as has already been explained in connection with Figs. 2 and 4.

The construction shown in Fig. 14 differs from what is shown in all the other figures, in that the bulb or body member 43, which, as in the other figures, is of translucent plastic material, preferably Lucite, has two threaded openings in the top and bottom respectively thereof, the top opening receiving therein the threaded screw 44 having a head 45 and the lower opening receiving a short threaded piece 46 into the lower exposed end whereof is received the internally threaded socket member 47 that itself may receive a wire cable end, not shown. The bulb or body member 43 has a through-window or opening 48 and under the screw head 45 is received a short link 49 which at its other end is provided with an opening 50 by which the link may be readily secured to any spark plug or any desired part of the mechanism.

In Fig. 15 I have shown in longitudinal central section a form of my invention which is the same in all respects as that shown in Fig. 2 and therefore bearing the same reference numerals as in Fig. 2 but with a prime added excepting that the member 17' is provided with a set screw 51 and the member 16' is provided with an adjusting screw 52. Both of these screws may be turned by a screw driver so that their inner ends may be brought into contact with an inserted gauge, as already explained in connection with other figures.

In the construction shown in Figs. 5 to 10, the body member is shown as rectangular in cross section, but it may be circular. In all the forms the shape of the body member may be varied as desired.

In all the embodiments the adjustable elements may be adjusted by a screw-driver inserted in the transverse slot in the end thereof.

When the spark intensifier is mounted on top of the spark plug, and in those cases where a window is provided, I desirably cover the window by some suitable adhesive material as, for example, Scotch tape.

75 I preferably do not provide the window, al-

though my invention includes the provision thereof, as shown in many figures of the drawing, and for that reason the construction shown in Fig. 7 and also that shown in Fig. 16 represent the preferable constructions.

The construction shown in Fig. 16 in side elevation is substantially the same as that shown in section in Fig. 7, and the same reference numerals are provided with a prime to indicate the same parts. The difference between the two constructions shown in Figs. 7 and 16 respectively is that in Fig. 7 the spark intensifier is secured by screw 19 directly upon the spark plug indicated at 18, whereas in Fig. 16 I provide a sleeve extension as in Fig. 2 at 17 and in Fig. 12 at 36 which is slotted along diametrically opposite lines, so that it may be fitted onto the spark plug.

So far as I am aware, Lucite has never been used for my purpose. I have tested many materials and find that Lucite is best adapted for my purpose. Particularly because it can be very readily and successfully machined as by providing sharply defined screw threads in the wall thereof, so as to receive threaded electrodes. I am aware that Bakelite and porcelain have been proposed, but neither of these is transparent. Although Bakelite may be termed translucent in very thin layers, it is not so satisfactory for applicant's purpose as Lucite, and certainly is not so nearly transparent. I am also aware that glass has been proposed. While this is transparent, it is not adapted to be readily and successfully machined as by providing well-defined screw threads to receive the threaded electrodes.

As stated, the distributor head or cup is preferably constructed of plastic material. Preferably it is made completely of clear Lucite, and preferably embodies the spark intensifier integral therewith, or the spark intensifier construction may be removably and adjustably attached thereto.

This intensifier principle, as herein disclosed, may also apply directly to a spark plug. The intensifier may be molded over the upper spark plug portion, having in such case a spark gap head instead of a screw head.

Having thus described several embodiments

of the invention, it is to be understood that although specific terms are employed, they are used in a generic and descriptive sense and not for purposes of limitation, the scope of the invention being set forth in the following claims.

I claim:

1. A spark intensifier for spark plugs of automobile and other internal combustion engines, comprising a complete, one-piece body member 10 of readily machined clear Lucite material that is transparent so that the spark light may be clearly seen, said body member being axially internally machine screw threaded, screws threaded respectively and directly into said threads in the body member and extending longitudinally axially therefrom, and having their inner ends adjustably spaced apart from each other merely sufficiently to provide a spark gap, tubes of conducting material, having closed inner ends and there abutting directly and respectively against the end walls of said body member and held directly upon said screws respectively, each of said tubes having an open outer end to receive detachably an element of the ignition system, at least one of said tubes being longitudinally slotted providing two springy parts to be snapped into circumferential gripping engagement with a spark plug member or the like.

2. A spark intensifier for spark plugs of automobile and other internal combustion engines, in accordance with claim 1, wherein said body member has a transversely extending window opening to the spark gap for air circulation.
